UNITED STATES PATENT OFFICE.

DANIEL W. CAMPBELL, OF LA CROSSE, WISCONSIN, ASSIGNOR TO THE VOUGHT-BERGER COMPANY, A CORPORATION OF WISCONSIN.

TELEPHONE SYSTEM.

SPECIFICATION forming part of Letters Patent No. 782,323, dated February 14, 1905.

Application filed June 21, 1904. Serial No. 213,446.

To all whom it may concern:

Be it known that I, DANIEL W. CAMPBELL, a citizen of the United States of America, and a resident of La Crosse, in the county of La 5 Crosse and State of Wisconsin, have invented certain new and useful Improvements in Telephone Systems, of which the following is a specification.

My invention relates to improvements in 10 telephone systems, and more particularly to that class commonly known as "multiple central-energy" telephone apparatus.

One of the objects of this invention is to 15 provide a telephone system having circuits which allow transmission of speech over solid conductors without the interference of relay-windings or relay-contacts.

Another object is to provide a telephone-circuit when both stations are plugged up 20 which permits the speech-waves to have a clear passage over both connecting-plug-cords without detrimental impedance or high resistance.

To these ends my invention consists of the 25 features of construction and combination of parts hereinafter described and claimed.

In the accompanying drawings, Figure 1 is 30 a diagrammatic view of my improved central-energy telephone system, which illustrates a complete central station and a pair of telephone instruments connected therewith; the parts being shown in normal position—viz., the receiver at the subscriber's station hung up and the plug at central out of connection 35 with the jack. Fig. 2 is a detail diagrammatic view showing the connection when the answering-plug is inserted in the jack at the central station and the receiver at the subscriber's telephone instrument is down, and 40 Fig. 3 is another detail diagrammatic view showing the connections when the receiver is hung up while the plug remains in said jack.

A and B represent two telephone instruments, C their respective lines, D their switchboard-jacks and switchboard apparatus, and 45 E the operator's connecting-cord circuit for working the same.

The following description applies equally to both sides of the system, they being num-

bered in accordance with the specifications 50 herein given.

The telephones A and B, of ordinary construction, have a switch-arm 3 connected with the side 4 of the instrument line-circuit C and the primary winding 14 of induction-coil 14^a 55 and condenser 3^b connected with the other side. The primary coil is also connected with the transmitter 15, which in turn is connected with the upper contact-point 17 of the switch. The lower contact-point 3^c is connected with 60 the call-bell 3^a, which in turn is connected with the condenser 3^b. The receiver 2 is connected with the secondary winding 3^d of the induction-coil.

The central switchboard apparatus consists 65 as follows: A battery F, the current of which is fed to the apparatus at the central exchange and to the telephone instruments, has a pair of main feed-wires 6 and 7 leading therefrom. The wire 4 of the instrument-circuit 70 is connected with the impedance-coil 5, which in turn is connected with the wire 6. The wire 4 is also connected with the spring side 35 of the jack D. The wires 4 6, with their impedance-coil, constitute what I have chosen 75 to term the "impedance-coil" side of the instrument and battery circuit. The wire 12 of the instrument-circuit is connected with the relay 10, which in turn is connected in series 80 with the impedance-coil 8, leading from the wire 7 of the battery-circuit. The wire 12 is also connected with the spring 23 or sleeve side of the jack D. The thimbles 24, which receive the sleeve side of the operator's plugs, 85 is connected with the wire 9 between the jack-relay 10 and the jack impedance-coil 8. The wires 12 and 7, with their connections, constitute what I have termed the "jack-relay" side of the instrument and battery circuit. The armature 18 of the relay 10 is permanently connected by the wire 18^a with the battery-wire 7, and when the relay is energized 90 the armature is drawn down and makes connection through the contact-point 18^b with the wire 19, which contains the lamp 20 and 95 is connected with the wire 6 of the impedance-coil side of the main circuit. When the relay 10 is energized by removing the receiver

2 from the switch-hook 3, the signal-lamp 20 is illuminated.

The answering-plug G is of ordinary construction and has its sleeve 27 connected by 5 the wire 26 with the relay 25, which in turn is connected with the main wire 7, leading from the battery, by means of the wires 25^a and 31. The tip 34 of the answering-plug G is connected, through, the wire 33, switch 42, 10 contact-point 43, wire 32, relay 29, contact-point 30, armature 28, wires 44 and 31, with the wire 7 of the main battery-circuit. The armature 37 is permanently connected by the wire 31 with the wire 7 of the battery-circuit 15 and by the local circuit-wire 40, containing the lamp 39 and the contact-point 38, with the wire 6 of the battery-circuit when the relay 29 is energized and the armature drawn down. The plug-circuits have connected 20 therewith a local telephone instrument H and a magneto-generator I in the ordinary manner.

When a subscriber takes down a receiver 2 from the switch-hook 3, a circuit is established as follows: hook 3, (at telephone instrument A,) wire 4, impedance-coil 5, wire 6, and positive battery, from negative battery over wire 7, impedance-coil 8, wire 9, relay-winding 10, wires 11, 12, 13, primary winding 14 of induction-coil, transmitter 15, wire 16, contact-point 17, and back to hook 3. The establishment of this circuit energizes relay 10, causing it to pull up armature 18 and complete a circuit from battery through wire 7, armature 18, wire 19, lamp 20, and wire 6 back to positive battery. This gives the switchboard operator the signal, whereupon the answering-plug G is inserted in jack D. This action short-circuits wire 22, relay 10, wire 11, jack-spring 23, and jack-thimble 24. This deenergizes relay 10, thereby releasing armature 18 and cutting out lamp 20. At the same time a clear talking-circuit is completed from negative battery, as shown in 45 Fig. 2, through the relay 25, wire 26, plug-sleeve 27, jack-sleeve spring 23, wires 12 and 13, induction-coil 14, transmitter 15, wire 16, hook-switch contact 17, hook-switch 3, wire 4, impedance-coil 5, and wire 6 back to positive battery. The energizing of relay 25 causes its armature 28 to pull up, cutting out the relay 29. When the subscriber is through talking, he will then hang the receiver 2 on the hook 3, which opens the instrument-circuit. This cuts the battery off of the sleeve side of the jack and causes the relay 25 to release its armature 28. This armature will then rest against the relay-contact 30, and the current flows, as shown in Fig. 3, from 55 negative battery through wire 31, armature 28, contact-point 30, relay-winding 29, wire 32, wire 33 to the tip 34 of the plug G, jack-spring 35, wire 36, impedance-coil 5, and wire 6 to positive battery. This causes the armature 37 of the relay-winding 29 to swing down 60

and make contact with the contact-point 38. The current then flows from negative battery through wire 31, armature 37, contact-point 38, disconnect-lamp 39, wires 40 and 6 to the positive battery and notifies the operator that 70 the instrument is not in use. As soon as the plug G is pulled out of the jack all of the relay-armatures fall into normal position and cut the lamp 39 out, as shown in Fig. 1.

Current is fed from the battery F to the 75 telephone instrument when connected to the central apparatus through the impedance-coil 5 on one side of the line. On the other side of the line the current is fed through the relay 10, impedance-coil 8, and relay 25 in multiple. The relay 10, impedance-coil 8 in series, and relay 25 in multiple with these two have a combined resistance equal to that of impedance-coil 5 for the purpose of distributing the current equally without what is 85 commonly known as "impedance effect" or "high resistance" when the talking-circuit is completed.

Having described my invention, what I claim as new, and desire to protect by Letters 90 Patent, is—

1. A telephone-line, a telephone-switch at the station thereof for changing the circuit of the line in the use of the telephone, a spring-jack for the line, a call-signal at the switchboard, a plug, a plug-circuit for making connection with said jack, a call-signal relay on the line-circuit at the switchboard, an impedance-coil in series with said relay, a disconnect-lamp circuit at the switchboard, a relay in the plug-circuit to open said disconnect-lamp circuit when the telephone is in use, and a main impedance-coil in the line-circuit equal in resistance to that of the combined resistance of the call-signal relay and the call-signal impedance-coil in series and the disconnect-lamp relay in multiple with these two. 100

2. A telephone-line, a telephone-switch at the station thereof for changing the circuit of the line in the use of the telephone, a spring-jack for the line, a call-signal at the switchboard, a plug, a plug-circuit for making connection with said jack, a call-signal relay in the line-circuit at the switchboard, an impedance-coil in series with said relay, a disconnect-lamp circuit at the switchboard, a relay to open said disconnect-lamp circuit when the telephone is in use, an auxiliary relay to close said disconnect-lamp circuit when the telephone-circuit is made with said jack and the telephone out 110 of use, and a main impedance-coil in the line-circuit equal in resistance to that of the combined resistance of the call-signal relay and the call-signal impedance-coil in series and the disconnect-lamp relay in multiple with these 115 two. 120

3. A telephone-line, a telephone-switch at the station thereof for changing the circuit of the line in the use of the telephone, a spring-jack for the line, a plug, a plug-circuit for 130

making connection with said jack, call and disconnect signaling means at the switchboard, a system of impedance and relay coils connected with said circuit for controlling the 5 operation of said signaling means, and a main impedance-coil connected with said line and equal in resistance to the combined resistance of said system of impedance and relay coils, for the purposes specified.

10 4. In combination with a telephone-line, a telephone-switch at the station thereof for changing the circuit of the line in the use of the telephone, a jack for the line, a call-signal at the switchboard, a plug-circuit for making connection with said jack, a call-signal relay 15 10 at the switchboard, an impedance-coil 8 in series with said relay, a relay 25 in said plug-circuit, an auxiliary relay 29 also in said plug-circuit, a disconnect-lamp and circuit opened 20 and closed by said auxiliary relay, said relay 25 adapted to control the operation of said auxiliary relay, and a main impedance-coil 5 in the line-circuit equal in resistance to the

combined resistance of the relay 25 and the resistance of the relay 10 and impedance-coil 25 8 in series.

5. A telephone-line, a telephone-switch at the station thereof for changing the circuit of the line in the use of the telephone, a jack for the line, a call-signal at the switchboard, 30 a plug, a plug-circuit for making connection with said jack, a disconnect-lamp, a disconnect-lamp circuit at the switchboard, a main impedance-coil in the line-circuit, and a system of relays and impedance-coils at the switchboard connected with said circuits having a 35 combined resistance equal to that of said main impedance-coil.

In testimony whereof I have signed my name to this specification in the presence of two sub- 40 scribing witnesses.

DANIEL W. CAMPBELL.
